UNITED STATES PATENT OFFICE.

SAMUEL R. VAN HORNE, OF CHICAGO, ILLINOIS, ASSIGNOR, BY MESNE ASSIGNMENTS,
TO SEFTON MANUFACTURING CORPORATION, OF MILLBROOK, NEW YORK, A COR-
PORATION OF NEW YORK.

FOLDING BOX.

1,237,424.

Specification of Letters Patent. Patented Aug. 21, 1917.

Application filed October 20, 1913. Serial No. 796,147.

To all whom it may concern:

Be it known that I, SAMUEL R. VAN HORNE, a citizen of the United States, residing at Chicago, in the county of Cook and 5 State of Illinois, have invented certain new and useful Improvements in Folding Boxes, of which the following is a specification.

My invention relates to folding boxes made of paste-board, corrugated board, or 10 the like, and the object thereof is to provide a box of this character with simple and efficient locking means for the flaps thereof.

In the drawing, Figure 1 is a top plan view of a box embodying my invention; Fig. 2 a 15 perspective view of the upper portion of such box illustrating the method of closing the flaps and inserting the new locks in place; Fig. 3 a sectional elevation on the line 3—3 of Fig. 2, but showing the large or 20 main flaps in different positions, and Figs. 4 5, 6 and 7 different views of a modified form of construction, Fig. 4 being a plan view of the blank; Fig. 5 a top plan view of the box partially folded; Fig. 6 a vertical section of 25 the box partially folded; and Fig. 7 a perspective view of the top of the box illustrating the last act in the folding operation.

Referring to the embodiment of my invention as herein shown in Figs. 1 to 3, the box 30 comprises a series of four side walls 1, hinged or connected together and made of any suitable material. Each end of the box is similarly provided with closure flaps so that the description of one end of the box 35 will suffice for both. There are in the present instance four flaps at each end, comprising the two opposite flaps 2, 2, which are similar to the two opposite flaps 3 and 4 which, while opposite to each other and of 40 the same general dimensions, differ in the respects hereinafter explained.

The two flaps 2, 2 are each provided with slits 2^a formed by cutting the flaps in the manner clearly shown in Figs. 1 and 2 at a 45 point adjacent their hinge lines and intermediate the length thereof.

The flap 3 is provided at each side edge, that is, at each of the edges perpendicular to its hinge line, with a hooked locking 50 tongue 5 which is of the peculiar shape illustrated in the drawing, the same being hinged at one end to its flap but separated therefrom by the cut *a* as to the remainder of its length, with the result that the portion of 55 such flap adjacent the cut extends back-

wardly toward the hinge line along and parallel with the edge of the flap. This flap is also provided with slits 3^a in which are inserted the corner tongues 4^a of the flap 4. In practice the entire box is made from a 60 single blank, and in cutting and scoring the blank the locking tongues 5 are taken from the body of the flaps 2 which accounts for the recesses shown therein. In Fig. 1 the bottom end flaps are shown as closed, while 65 the top end flaps are shown as open.

In closing either end of the box the two opposite flaps 2 are first folded inwardly to the position shown in Fig. 2. The flap 3 is thereupon folded over but in this operation 70 it is itself folded or bent back along its central longitudinal axis in the manner shown in Fig. 2, with the result that the locking tongues 5 partake of the vertical position shown so as to readily enter the slits 2^a. After 75 the tongues have entered or partially entered the slits the flap 3 is then folded down to horizontal position whereby the tongues hook backwardly through the slits and assume the position shown in Fig. 3, at which 80 time an edge of each tongue bears firmly against the under side of a flap 2 along its hinge line. The flap 3 is thereby held or locked in position but not against the application of positive force, as the flap may be 85 opened by reversing the described operation. After the flap 3 is in its flat condition the other flap 4 is folded over and the tongues 4^a inserted in the slits 3^a. The box is now 90 double locked, being first locked by the locking tongues 5 and being secondly locked by the tongues 4^a.

In Figs. 4, 5, 6 and 7, I have illustrated a modified form of construction embodying the same invention in its broader aspect. 95 In this form the box is made of the blank illustrated in Fig. 4, the resulting box being a square one, although as obvious the box may have any desired size and proportions. By suitable cutting and scoring the box is 100 divided into the four side walls 6, 7, 8 and 9. The wall 7 has similar rectangular flaps 10 hinged to two opposite edges and each of these flaps has hinged on its opposite side edges corner flaps or extensions 11 105 which are of sector form. On the hinge lines between the flaps 10 and 11 and intermediate the length of such lines are short slots 12 and in the body of each of the flaps 10 near their inner hinge lines are the 110

irregular shaped slits 13. The flaps or extensions 11 are separated from the walls 6 and 8 by the cut lines 14. One of the outermost walls 9 is hinged to two opposite edges, 5 similar flaps 15 terminating at their outer free edges in the pairs of tongues 16. This wall 9 also has on its outermost edge a short hinged flap 9^a which is adapted to be pasted or glued to the side wall 6. The 10 two flaps 15 are each provided intermediate the length of two opposite sides with hooked locking tongues 17 similar to the tongues 5 in the first described construction. The box illustrated thus has similar 15 top and bottom closures although as will be understood my invention may be used in only one of the closures although I prefer that it shall be used with respect to both.

20 The box is formed or assembled from the blank shown in Fig. 4 by attaching the walls 9 together by means of the pasting flap 9^a, thereby forming the body of the box. In order to form the bottom of the 25 box one of the walls 10 is now folded over with its segmental flaps 11 inserted within the box, as shown in Fig. 6. One of the flaps 15 is thereupon folded over and its locking tongues inserted in the slits 12 in 30 the same manner as hereinbefore described and as clearly illustrated in Fig. 7 wherein it is seen that the flap 15 is bent back so as to bring the tongues in insertible position with respect to the slots 12. The flap 35 is thereupon folded downwardly flat upon the flap 10 and the tongues 16 are inserted in the slits 13. The box now partakes of the form illustrated in Fig. 5, being ready to have its contents introduced and the top 40 closure is manipulated in the same manner as the bottom closure.

I claim:

1. A box comprising side walls hinged together and inwardly folding end closure 45 flaps hinged thereto, a slit being formed in and along the hinge line between one

flap and the side wall adjacent thereto, and a second flap, folding over said first flap at right angles thereto having a locking tongue hinged to its side edge and extending 50 rearwardly from the hinge line of the tongue along the side edge of the flap toward the hinge line of such flap, whereby the locking tongue may be hooked back through the slit in said first flap when said second flap is bent to throw the free end of the tongue forwardly into the slit.

2. A box comprising side walls hinged together and inwardly folding end closure flaps hinged thereto, one of said flaps being 60 formed with a hinge line lying along the top of one of the side walls and a slit being formed in and along said hinge line, and a second flap arranged to fold over said first flap having one side edge adjacent said 65 hinge line when said flaps are folded and having a locking tongue hinged to its side edge and extending rearwardly from the hinge line of the tongue along the side edge of the flap toward the hinge line of such 70 flap, whereby the locking tongue may be hooked back through the slit in said first flap when said second flap is bent to throw the free end of the tongue forwardly into the slit. 75

3. A box comprising walls connected together and flaps hinged thereto, one of said flaps having a slit formed in and along its hinge line, and a second flap arranged to fold over said first flap having a locking 80 tongue hinged to its side edge and extending rearwardly from the hinge line of the tongue along the side edge of the flap toward the hinge line of such flap, whereby the locking tongue may be hooked back through the slit in 85 said first flap when said second flap is bent to throw the free end of the tongue forwardly into the slit.

SAMUEL R. VAN HORNE.
